United States Patent Office

Des. 175,715
Patented Oct. 4, 1955

175,715

HOSIERY HOLDER

Florence S. De Forte, Buffalo, N. Y.

Application February 28, 1955, Serial No. 34,733

Term of patent 14 years

(Cl. D80—9)

Fig. 2

Fig. 3.

Fig. 4.

Fig. 1.

Fig. 1 is a front elevational view of a hosiery holder showing my new design, the opposite side being similar in appearance.

Fig. 2 is a top plan view;

Fig. 3 is an end view taken from the left of Fig. 1;

Fig. 4 is an end view taken from the right of Fig. 1; and

Fig. 5 is a bottom plan view thereof.

I claim:

The ornamental design for a hosiery holder, substantially as shown.
